ATTORNEY.

UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC-LAMP INSTALLATION.

1,261,928.

Specification of Letters Patent.

Patented Apr. 9, 1918.

Application filed April 5, 1917, Serial No. 160,065. Renewed February 23, 1918. Serial No. 218,896.

To all whom it may concern:

Be it known that I, MONROE GUETT, a citizen of the United States, and a resident of Hartford, in the county of Hartford, 5 State of Connecticut, have invented certain new and useful Improvements in Electric-Lamp Installations, of which the following is a specification.

The object of this invention is to provide 10 a novel construction and arrangement of a lamp socket, which, when in its normal position with the lamp connected into the electrical circuit, is inaccessible for the purpose of the insertion or removal of a lamp, but 15 which may be swung out of normal position in order to permit of such insertion or removal. A particular instance where such a construction is advantageous is in the manufacture of relatively small lamp receptacles of the type commonly used as 20 pilot or signal lights, which are preferably of very compact construction, the receptacle being recessed to receive the lamp but not affording sufficient room to manipulate 25 a lamp with a standard threaded base to cause its engagement with the socket.

By my invention I provide a pivotal mounting for the socket so that it can be swung out of normal position for the purpose of inserting or removing the lamp. 30 The threaded connection has obvious advantages over other types such as spring fingers to grip the lamp base.

In the accompanying drawings—

Figure 1 is a plan of a simple form of 35 pilot lamp receptacle in which my invention is embodied.

Fig. 2 is a section on the line 2—2 of Fig. 1.

Fig. 3 is a perspective view of the complete socket.

Fig. 4 is an edge view of the socket member.

Fig. 5 is a perspective view of a modification.

Referring to the drawings, *a* denotes the receptacle, *b*, *b*, the binding posts for the circuit wires, *c* denotes the lamp arranged horizontally in the receptacle and with its 50 base engaging a pair of terminals, one of which is connected to one binding post, and the other to the other binding post.

These lamp terminals comprise a spring arm 10 adapted to contact with the center 55 contact 12 of the lamp base, and a socket

13 into which the shell 14 of the lamp base is threaded. As clearly seen in Fig. 3 this socket comprises a bifurcated member 15, between the arms of which is pivotally supported a socket member 16 by the trunnions 17, in order that the socket member may be turned out of horizontal position while the lamp is being screwed into or out of it, and when the lamp has been inserted it may be turned into horizontal position. 60 The thread engagement of the lamp base with this socket member permits of positively positioning the center contact 12 so that it will bear against the spring arm 10 and insure that this contact shall always 70 be maintained.

As here shown the socket member consists of a spirally formed single convolution of stock of proper thickness to engage and move in the thread of the complementary member. In other words, it is a solid annulus with its wall increased in width at that part where the stock is axially displaced to give the spiral formation, the oblique connecting portion 20 being notched 80 on its inner edge as at 21 in order to permit of entering the thread of the male member. While this is the preferred form of the socket member, still I am aware that other arrangements, one of which is illustrated in Fig. 5, and consists of a split spiral ring 25, might be substituted. The distinguishing characteristic is the pivotal support for the socket member which permits it to be turned out of normal position 90 for the insertion and removal, for instance, of a lamp. Provision is also made for retaining the socket member in position to permit of inserting a lamp, as for instance 95 by the notch 26 which snaps down onto one side of the socket member.

In accordance with the provisions of the patent statutes I have described the principle of operation of my invention, together with the apparatus which I now consider to represent the best embodiment thereof; but I desire to have it understood that the apparatus shown is only illustrative, and that the invention can be carried out by other means. 100

I claim as my invention:

1. In a device of the character described, a pair of co-operatively arranged circuit terminals, one of which is a socket member, a lamp having threaded engagement with said 110

socket member and adapted in the normal position of said socket member to contact with the other circuit terminal, means to prevent the disengagement of the lamp from the socket member when the latter is in normal position, and a pivotal mounting for said socket member to permit of moving it with the supported lamp into and out of normal position.

10 2. A lamp socket comprising a stationary bifurcated member and a socket member positioned between the arms thereof, and cooperating parts on said socket member and arms constituting a pivotal mounting for said socket member.

3. A lamp holder comprising a ring-shaped socket member and trunnions projecting radially from opposite sides thereof.

4. In a device of the character described, a base of insulating material recessed to receive a lamp, a lamp closely fitting said recess and having a screw base, a fixed contact in the recess at one end thereof, a ring contact spaced from said fixed contact and adapted to receive the screw base of said lamp, and a pivotal mounting for said ring contact on which it, with its supported lamp, may be turned out of normal position to permit of the removal of the lamp therefrom.

5. In a device of the character described, a base of insulating material recessed to receive a lamp, a fixed contact in the recess at one end thereof, a ring contact spaced from said fixed contact and with its axis

normally parallel with the top of the base, and a pivotal support for said ring contact on which it may be turned out of normal position to permit of securing a lamp therein.

6. In a device of the character described, a base of insulating material recessed to receive a lamp, a fixed contact in the recess at one end thereof, a split ring contact spaced from said fixed contact and with its axis normally parallel with the top of the base, and a pivotal support for said split ring contact on which it may be turned out of normal position to permit of securing a lamp therein.

7. In a device of the character described, a base of insulating material recessed to form a lamp-receiving chamber, a fixed contact at one end of said chamber, a bifurcated member mounted in said chamber and spaced from said fixed contact, a ring provided with outwardly projecting diametrically opposite trunnions supported in said bifurcated member, said ring being adapted to receive the base of a lamp and support it in position with its axis parallel with the top of the base.

8. A lamp socket comprising a bifurcated member and a socket member positioned between the arms thereof, and cooperating parts on said socket member and arms constituting a pivotal mounting for said socket member, and means for holding said socket member when out of normal position.

MONROE GUETT.
